COMBINED DENTAL TRAY AND SUPPORT ARM THEREFOR

Robert A. Olsen, Palatine, Ill., assignor to American Hospital Supply Corporation, Evanston, Ill., a corporation of Illinois

Filed Sept. 20, 1967, Ser. No. 8,675

Term of patent 14 years

(Cl. D24—1)

FIG. 1

FIG. 2

FIG. 1 is a perspective view of a combined dental tray and support arm therefor, showing my new design;

FIG. 2 is an enlarged fragmentary perspective view thereof;

FIG. 3 is a top plan view;

FIG. 4 is a bottom view;

FIG. 5 is a side elevation looking in the direction of line 5-5 of FIG. 3;

FIG. 6 is a side elevation looking in the direction of line 6-6 of FIG. 3;

FIG. 7 is an elevation looking in the direction of line 7-7 of FIG. 3; and

FIG. 8 is an elevation looking in the direction of line 8-8 of FIG. 3.

The broken lines are shown for illustrative purposes only.

I claim:

The ornamental design for a combined dental tray and support arm therefor, substantially as shown and described.
